United States Patent Office.

WILLIAM G. HERMANE, OF ALBANY, NEW YORK.

Letters Patent No. 62,268, dated February 19, 1867.

IMPROVEMENT IN LIFTING-JACK.

The Schedule referred to in these Letters Patent and making part of the same.

Be it known that I, WILLIAM G. HERMANE, of the city of Albany, State of New York, have invented a new Carriage Jack, for lifting carriages in order to remove their wheels when required; and I declare the following specification, with the drawings forming part thereof, to be a full and complete description of my invention.

Figure 1 represents in perspective the jack placed under the axle of a carriage and ready for service.

Figure 2 is a diagram of the jack with the wheel lifted up from the ground.

Similar letters denote the same parts of the apparatus.

The jack consists of a base of plank, A, upon which stands an upright standard, B, of thick plank, its outer edge, C, perpendicular, its inner one, D, tapering from its bottom upward. Fitted to this, edgewise, is a movable or sliding piece, E, of the same material, its outer edge being perpendicular, and its inner, G, tapering from top to bottom in reverse of D, against which it slides. E is held against B and kept in place by metal plates or grips H H fastened on each side of it, and projecting beyond its edge over B, with their edges moving in a groove, a a, cut for that purpose, parallel with and a short distance from the edge of B. The upper end of E is formed into steps, b b, for the purpose of adapting its height to that of different axles as they vary in height from the ground. In order to raise and lower E a forked lever, K, whose arms embrace B and a portion of E, is pivoted at e. Between the arms, at their inner extremity, a roller, f, is fitted, which is entered into E by the slot g, cut out of it in the manner shown, so that moving the lever will raise or lower E, the roller revolving against the upper edge of the slot. In the upper part of B, in its inner edge, a slot, h, is made at such place as to coincide with the slot g when it is raised to its highest position by the lever, and so as to permit the roller f to pass into and lie partially within it, as shown in fig. 2, where the roller is shown with two-thirds of its body lying in slot h. It will be seen from the diagram, that when the roller is in that position any pressure of E downward will tend to force the roller against the back of slot h, leaving enough of its surface projecting into slot g to block E from descending, and hold it firmly in its place, rendering it impossible for any load to force down E, unless from the destruction of the machine, and separation of its parts. It depends upon no pins or other stops to keep it secure. The existence of a lead upon it holds it safely. The simplicity of this arrangement makes this jack superior to any of its kind now in use. The roller f may be dispensed with, and a solid block be used in its place, but it is manifest that a roller would be preferable.

What I claim as my invention, and desire to secure by Letters Patent, is—

The lever K, constructed as described, in combination with the standard B and sliding-piece E, and their slots g and h, opening together in the manner and for the purposes set forth in this specification.

WM. G. HERMANE.
